TUFTING BUTTON

Wilfred B. Mathewson, North Weymouth, Mass., assignor to United Mattress Machinery Company, Quincy, Mass., a corporation of Maine

Application August 30, 1932. Serial No. 631,055

9 Claims. (Cl. 24—90)

This invention relates to tufting buttons such as are used in tufting mattresses or in upholstery work and it has for its general object to provide a novel tufting button which is simple and inexpensive to manufacture but which can be easily attached to or detached from the tufting cord which ties the button to the mattress, cushion or other article.

My improved tufting button has a convexly curved back face and is provided with a cord-receiving passage extending through the button from one side to the other of said back face and is also formed with an entering slot in the convex back face which leads to the cord-receiving passage and through which the tufting cord can be entered into the passage.

In the preferred embodiment of my invention the button is in the general form of an ellipsoid, the cross section of the button taken along the minor axis, that is, an axis extending from the front to the rear face, being in the form of an ellipse.

The button is so constructed that the portion thereof with which the tufting cord engages is located within the boundaries of the ellipsoidal shape and do not present any projections or protuberances that extend beyond said boundaries. The button, therefore, has a substantially smooth surface both on the back face and the front face.

In inserting the button into a loop of tufting cord said button is turned bottom side up with the front face against the mattress and then the edge of the button adjacent the entering slot is crowded into said loop. This will cause the loop to enter the slot and when the loop has reached the inner end of the slot where it communicates with the cord passage the button is reversed in position to bring the back side against the mattress and the front side exposed. During this reversing operation the loop of tufting cord drops into the cord passage and the button is locked in position.

In order to give an understanding of the invention I have illustrated in the drawing a selected embodiment thereof which will now be described after which the novel features will be pointed out in the appended claims.

Fig. 1 is a view of a tufting button embodying my invention showing it attached to the tufting cord;

Fig. 2 is a section on the line 2—2, Fig. 1, said section also showing the button in section on the line 2—2, Fig. 3;

Fig. 3 is a back side view of the button;

Fig. 4 is a section on the line 4—4, Fig. 3;

Figs. 5, 6 and 7 show different steps in the operation of attaching the tufting button to a loop of tufting cord.

The button embodying my invention is indicated generally at 1, and 2 indicates a portion of a mattress, cushion or other device with which the tufting button is used. The tufting button is attached to the mattress or cushion by means of a tufting cord 3 which extends through the mattress and is formed with a loop portion 4 with which the tufting button has engagement.

The tufting button is ellipsoidal in shape and both the front face 5 and the rear face 6 have a convex curvature. A cross section through the button on the minor axis (that is, the axis extending from the front to the rear face) will have the general shape of an ellipse as shown best in Figs. 2 and 4. The shape of the button when looked at in the direction of the minor axis 75 will preferably be circular as shown in Fig. 3.

While a button having this shape may be made in various ways and of any desired material I have shown herein a button which is hollow and which is formed by connecting together a concavo-convex front member 7 and a concavo-convex rear member 8. The peripheral edge 9 of the front member 7 is shown as embracing the peripheral edge 10 of the back member 8 and said peripheral edge 9 of the front member is bent around the edge 10 of the rear member thereby locking the two members together and forming a hollow ellipsoidal-shaped button.

The button is provided with a cord-receiving passage 11 which extends therethrough from one side to the other of the convex rear portion of the button.

The rear member 8 of the button is also provided with an entering slot 12 which leads to the cord-receiving passage 11 and through which the loop 4 of the tufting cord is introduced into the passage 11. This slot 12 is an open slot and will preferably lie in a plane substantially at right angles to the minor axis or parallel to a major axis but is formed entirely in the rear member 95 8. The slot is formed at its inner end with an offset portion 13 which communicates directly with the cord-receiving passage 11, this offset portion serving as a means to lock the loop of tuft in the passage.

In attaching the button to the loop 4 of tufting cord the edge 14 of the button will be placed on the surface of the mattress 2 with the front face 5 in engagement with the mattress, that is, it will be placed on the mattress in inverted posi- 110

tion. The edge 14 of the button adjacent the slot 12 is then inserted into and through the loop 4 of tufting cord as shown in Fig. 5 and during this operation the tension to which the 5 cord is submitted will naturally draw the loop into the slot 12.

The button is forced through the loop 4 while still in its inverted position until the loop arrives at the inner end of the slot 12 as shown in Fig.

10 6. The button is then turned in the direction of the arrow Fig. 6 to place it right side up and during this turning movement the button will turn about the loop 4 of the tufting cord as an axis. As the button assumes its right-side-up 15 position as shown in Fig. 7 the loop of the cord will be drawn into the cord-receiving passage 11 where it will be held by the tension to which the cord is subjected.

The button can be readily removed from the 20 tufting cord if desired either by reversing the above operation or by turning the button about the cord as an axis in an anti-clockwise direction from the position shown in Fig. 7 until the loop of the cord slips out of the slot 12.

25 7. The button embodying my invention is simple in construction and inexpensive to manufacture and the portions thereof which engage the cord are located entirely within the ellipsoidal outline of the button so that said button presents no 30 cord-engaging projections or protuberances.

One advantage resulting from this construction is that the loop 4 of tufting cord to which the button is to be attached is visible to the operator during the entire time that the button is 35 being inserted. This results from the fact that the button is inserted underneath the loop as shown in Fig. 5 so that the loop is on the upper side of the button until it enters the slot. The operative can then readily observe the operation 40 of entering the loop into the slot. Because of the fact that the slot 12 is an open slot the loop 4 of tufting cord can be entered through said slot and into the cord-receiving passage without bending or flexing any portion of the back 45 member of the button. The open slot allows the free passage of the loop of tufting cord therethrough and the shape of the slot serves to retain the loop in the cord passage after the button has been placed in position.

50 8. I claim:

1. A tufting button having a convex rear face free from projecting portions and provided with a cord-receiving passage extending therethrough from one side to the other of said convex rear 55 face, and also having a permanently open entering slot formed in said rear face and leading to said passage.

2. A tufting button having a convex rear face and provided with a cord-receiving passage extending therethrough from one side to the other of said convex rear face, and also having an 60 L-shaped entering slot formed in said rear face and leading to said passage.

65

70

75

3. An upholstery button having an ellipsoidal shape and presenting a smooth rear face free from projecting portions, said button being provided with both a cord-receiving passage extending therethrough from one side to the other of the rear face and an entering slot formed in the rear face and leading to said passage, said slot having an offset portion at the end which communicates with the passage.

4. A tufting button having an ellipsoidal shape and provided with a cord-receiving passage extending therethrough from one side to the other of the rear convex face and also having an entering slot situated in a plane nearer the center of the button than said passage, said slot having an offset portion at its inner end leading to the 90 passage.

5. A tufting button having an ellipsoidal shape and provided with a cord-receiving passage extending therethrough from one side to the other of the rear convex face and also having a permanently-open entering slot leading to said passage and situated in a plane nearer the center of the button than said passage.

6. A tufting button having a convex rear face free from projecting portions and provided with a cord-receiving passage extending therethrough from one side to the other of said convex rear face, said rear face also having a permanently-open entering slot formed therein which leads to said passage and which is situated nearer the center of the button than said passage.

7. A tufting button having an ellipsoidal shape and formed with a front member and a rear member each of sheet material, the rear member having two cord-receiving openings disposed on opposite sides of its center, and also having an entering slot connecting said openings, the ends of the slot which lead into said openings being offset.

8. A tufting button having a connecting front member and a rear member each made of sheet material, the rear member having a convex face and provided with two cord-receiving openings disposed on opposite sides of the center of the button, and also being provided with an open entering slot connecting said openings, and through which a loop of tufting cord may be entered into said openings without flexing any portion of the back of the button.

9. A tufting button having a connected front member and a rear member each made of sheet material, the rear member having a convex face and provided with two cord-receiving openings disposed on opposite sides of the center of the button, and also being provided with an open entering slot connecting said openings and through which a loop of tufting cord may be entered into said openings without flexing any portion of the back of the button, the ends of the slots which enter said openings being offset.

WILFRED B. MATHEWSON.
